UNITED STATES PATENT OFFICE

171,469

PIN AND NAIL REMOVING TOOL

Morris Stock, New York, N. Y.

Application July 2, 1953, Serial No. 25,768

Term of patent 14 years

(Cl. D54—13)

To all whom it may concern:

Be it known, that I, Morris Stock, a citizen of the United States, residing at 149 West Tremont Avenue, in the county of Bronx, city and State of New York, have invented a new, original, and ornamental Design for a Pin and Nail Removing Tool, of which the following is a specification, reference being had to the accompanying drawing, forming part thereof, in which

Fig. 1 is a perspective view of a pin and nail removing tool showing my new design;

Fig. 2 is a bottom plan view thereof; and

Fig. 3 is an elevational view looking at the right end of Fig. 2.

I claim:

The ornamental design for a pin and nail removing tool, as shown.

MORRIS STOCK.
